UNITED STATES PATENT OFFICE

MARSHALL BARNUM, OF NEW HAVEN, CONNECTICUT, ASSIGNOR TO THE ACME WIRE COMPANY, OF NEW HAVEN, CONNECTICUT, A CORPORATION

PROCESS FOR PRODUCING ELECTRIC COILS

Application filed October 11, 1929. Serial No. 398,873.

This invention relates to an improvement in processes or methods for producing electric coils and particularly electric coils which are impregnated or otherwise treated with a hot liquid for the purpose of insulating, excluding moisture, and for uniting the various parts into a homogeneous unit.

In the manufacture of electric coils of the type having absorbent fibrous core-tubes, it is the practice to impregnate the coil and core-tubes as a unit with a hot wax, pitch, or similar viscous-like liquid for the purpose, among others, of excluding moisture, improving insulation properties, and welding, so to speak, the various convolutions of the wire and the core-tube into a homogeneous whole.

One of the main objections to treating electric coils with liquids which are heated to increase their penetrative action, desirable though this is, is the fact that such treatment tends to soften the absorbent paper or other fibrous core and thus permit the same, together with the convolutions of wire wound thereon, to twist, warp, or otherwise become distorted from a predetermined form.

The object of this invention is to provide a method for the manufacture of electric coils of the type having tubular cores of absorbent fibrous material which will minimize warping and distortion and result in the production of uniform and workmanlike articles.

With the foregoing and other objects in view, my invention consists in a process for the manufacture of electric coils having certain novel features as will be hereinafter described and particularly recited in the claims.

In the accompanying drawings:

Fig. 1 is a perspective view of one of the many forms of electric coils which may be manufactured by means of my improved process;

Fig. 2 is a broken perspective view of a length of core-tube prior to the indurating treatment thereof for rendering the same impervious to hot impregnating liquids;

Fig. 3 is a corresponding view of the same after indurating treatment;

Fig. 4 is a perspective view of a short section of core-tube suitable for employment in the type of coil shown in Fig. 1 and indicated by stippling as indurated prior to the winding of the convolutions of wire thereon; and

Fig. 5 is a perspective view of an electric coil in the stage of its manufacture just prior to its treatment with a hot impregnating liquid, a portion of the paper insulation being broken away to expose the wire.

In carrying out my invention I apply to a length of core-tube 10, in any approved manner, treatment or coating 11, indicated by fine stippling in the various figures, to render the said tube, which is usually of paper or other relatively soft and permeable fibrous material, effectively resistant or indurate to the softening action of hot impregnating liquids or compounds, such as wax, resins, pitch, etc.

The liquid with which the core-tube 10 may be treated I will herein characterize, for descriptive purposes, as having indurative properties, and by the use of such term I wish to be understood as meaning its capacity for rendering the object treated effectively resistant to the softening or other deleterious effects of hot impregnating compounds, such as wax, resin, or pitch.

Many different substances may be employed as an indurating liquid, within the meaning of that term as herein employed, to impart to the fibrous core-tube the resistant properties above described. I have found, however, sodium silicate to be a desirable indurating substance for the reason that it is both low in cost and effective for the purpose intended. Other fluids have, however, proven satisfactory, such, for instance, as shellac, and numerous salts, which contain water of crystallization, so that when the latter is once evaporated, the core-tube is both stiff and resistant to hot impregnating fluids.

Preferably, I treat a length of core-tube

10, prior to severing it into the shorter core-pieces 12 (Fig. 4), though it is obvious that the individual core-pieces may be treated, if desired.

5 After the core-tube has been treated either in long lengths or individually to render it substantially impervious to hot impregnating liquids or compounds, a coil of wire 13 is wound thereon in any approved manner, together with a strip 14 of paper which is designed to be interposed between each layer of wire in accordance with usual practice. The resultant article has now assumed the form shown in Fig. 5.

15 The next important step in carrying out my invention consists in treating the unit comprising the coil of wire 13, paper strip 14 and core-tube 12 with an impregnating fluid of wax, resin, pitch, etc., which is applied hot to better cause it to penetrate into the paper 14 and all interstices in the coil-structure.

20 25 The impregnating fluid is preferably applied to the coil-structure by immersing the latter in a molten and highly-fluid bath of the desired constituents though, as is obvious, other methods of application may be employed.

30 When the hot impregnating fluid is applied to the coil-structure as above described, the same is prevented from so deleteriously affecting the core-tube 12, which is virtually the foundation of the coil, as to soften or weaken it to thereby permit distortion.

35 As a result of the employment of my improved process electric-coils may be produced which do not vary in size or form from a predetermined standard and therefore may be relied upon to fit into an assembly such as 40 radio-receivers, etc., without alteration.

I claim:

1. A process for the manufacture of electric coils of the type comprising a fibrous absorbent core-tube and a coil of wire thereon, consisting in treating the core-tube prior to the winding of the wire thereon with a liquid having the characteristic, when solidified, of being substantially impervious to hot impregnating liquids, thereafter winding a 50 coil of wire upon the core-tube so previously treated and then treating the core-tube and coil as a unit with a hot impregnating liquid; whereby during the latter treatment, the said core-tube is shielded from the softening and 55 weakening effects of the hot impregnating liquid and the distortion of the unit avoided.

2. A process for the manufacture of electric coils of the type comprising a fibrous absorbent core-tube and a coil of wire thereon, consisting in treating the core-tube prior to the winding of the wire thereon with a liquid having the characteristics, when solidified, of being substantially impervious to hot impregnating liquids and physically hard, thereafter winding a coil of wire upon the

core-tube so previously treated and then treating the core-tube and coil as a unit with a hot impregnating liquid; whereby during the latter treatment, the said core-tube is physically stiffened and shielded from the softening and weakening effects of the hot impregnating liquid and the distortion of the unit avoided.

In testimony whereof, I have signed this specification.

MARSHALL BARNUM.
